UNITED STATES PATENT OFFICE.

FREDERICK M. WHYTE, OF TARRYTOWN, NEW YORK, ASSIGNOR TO HUTCHINS CAR ROOFING COMPANY, OF DETROIT, MICHIGAN, A CORPORATION OF MICHIGAN.

CAR BODY.

Application filed December 6, 1917, Serial No. 205,776. Renewed November 17, 1922.

To all whom it may concern:

Be it known that I, FREDERICK M. WHYTE, a citizen of the United States of America, residing at Tarrytown, in the county of 5 Westchester and State of New York, have invented certain new and useful Improvements in a Car Body, of which the following is a specification, reference being had therein to the accompanying drawings.

10 The invention relates to car body construction and has more particular reference to the construction of the ends and sides of the car from metallic sheets. It is the object of the invention to obtain a maximum of strength 15 in a construction which may be readily formed from pressed sheets or plates, and further to combine with said construction a non-metallic lining without materially increasing the thickness of the wall. With 20 these objects in view the invention comprises the construction as hereinafter set forth.

In the drawings:

Figure 1 is a horizontal section through a portion of the end and adjacent side of a 25 car showing my improved construction;

Figure 2 is a vertical section on line 2—2 Figure 1;

Figure 3 is a cross section on line 3—3 Fig. 2;

30 Figure 4 is an elevation of one of the pressed sheets.

In the construction of railway box cars from metallic sheets the gauge or thickness of the metal is such as to impart but very 35 little strength to the wall in resisting stresses transverse thereto. Consequently it is necessary to provide a supporting frame to produce the necessary trussing and impart the desired rigidity to the structure. With 40 the present invention the frame may be dispensed with and the trussing produced by the cooperation of a pair of sheets, one of which is bent or embossed at intervals to separate the same from the other. A further 45 feature of my improvement is that it may be used in connection with a wood lined car, the studs or posts for securing the lining being arranged intermediate embossed portions of the metallic plates. This avoids 50 increase in the thickness of the wall, and combines in the one structure strength, rigidly and heat insulation.

In detail, A is a metallic plate, which is 55 pressed to form a series of inwardly-extending embossed portions B. C is an outer

plate arranged parallel and secured to the non-embossed portions of the plate A, and together with said plate constituting a truss. The ends of the car are preferably formed by two pairs of cooperating inner and outer plates arranged respectively upon the opposite sides of the longitudinal center line of the car and overlapping each other at the center. At the corners these plates are secured to the side plates of the car by rounded corner strips D, and the sides of the car may be formed by similar pairs of plates overlapping and secured to each other. At the base the plates A and B are suitably secured to the sill, and as shown in Figures 2 and 3 the sill E is in the form of an angle bar, the upwardly-extending flange E' of which is embraced by the plates A and B and secured thereto by riveting. A similar construction, as in Fig. 2, may be employed between the upper ends of the sheets and the side plates.

For certain uses cars with metallic walls are objectionable on account of condensation of moisture on the inner face of the metal. This may be avoided and the structure also strengthened and reinforced by the provision of a wooden lining. As shown this comprises the boards F which are secured to posts G arranged between the embossed portions B of the inner plates. The spaces between the posts G thus form pockets for receiving the embossed portions B, thereby decreasing the width which would otherwise be necessary. The posts G may be attached to the plates by suitable means, such as the bolts H, which are first riveted to secure the inner and outer plates to each other and then extend inward through the post G. Rivets I may be also arranged to connect the plates intermediate the bolts, as indicated in Figure 2.

In use, any shocks or stresses imparted to the walls of the car either from the outside or inside will be resisted by the truss formed by the outer and inner plates, and further by the reinforcement of the wooden lining. The wooden lining prevents condensation on the inner surface and additional heat insulation is obtained by the spaces between embossed portion of the inner and outer plates which are filled with confined air.

While I have specifically shown and described the embossed plate as associated with a flat plate, it is obvious that the embossed

plate is the chief factor in imparting rigidity to the structure.

What I claim as my invention is:

1. In a car body, a wall comprising metallic plates having portions parallel and adjacent and secured to each other, and portions spaced by the embossing of one of the sheets to constitute a truss, a lining for the wall adjacent to the embossed portions, and posts for supporting said lining in the spaces between said embossed portions.

2. In a car body, a wall comprising a metallic sheet having pan-shaped embossed portions, a cooperating sheet lying adjacent to the portions of the embossed sheet in its original plane and secured thereto, and posts secured to the adjacent portions of said sheets and arranged in the spaces between the embossed pan-shaped portions thereof.

3. In a car body, a wall comprising a metallic sheet having inwardly-embossed panel portions extending substantially from the sill to the plate, with intermediate and upper and lower portions lying substantially in the original plane, a cooperating outer metallic sheet lying adjacent to the portions in the original plane and rigidly secured thereto, posts arranged in the spaces between adjacent panels and secured to said sheets, and a lining secured to said posts and lying adjacent to the inwardly-embossed panels.

4. In a car body, an end wall comprising pairs of metallic sheets extending from the center to the sides and from the sill to the plate, the inner sheets having inwardly-embossed panel portions and portions intermediate said panel portions and above and below the same, lying substantially in the original plane, the outer sheets lying adjacent to the portions of said inner sheets which are in the original plane and being rigidly secured thereto, and the marginal portions of said sheets at the center of the car being overlapped, interspaced and secured to each other.

5. In a car end, a metallic plate, one dimension of which is substantially equal to one dimension of said end, said plate having marginal portions at the sides and ends thereof together with a central portion, all in the same general plane of the plate, embossed panel portions intermediate said central portion and the sides, extending in the same direction and located in a spaced parallel plane, and obliquely extending portions between the portions in the spaced planes at both sides and ends thereof, said panel portions extending uninterruptedly between said marginal and oblique portions at opposite ends thereof.

6. In a car end, a metallic wall comprising a plurality of metal plates, each of which has one dimension substantially equal to one dimension of said end, and said plates hav-

ing their adjacent edges rigidly secured to each other, each plate comprising marginal portions at the sides and ends in the same general plane, an embossed panel portion intermediate said marginal portions in a spaced parallel plane, and obliquely extending portions connecting the portions in the two planes at both sides and ends, said panel portion extending uninterruptedly between the marginal and obliquely extending portions at opposite ends thereof.

7. In a car wall, a metallic wall plate having marginal portions at the sides and ends in the same general plane, a rectangular embossed panel portion intermediate said marginal portions in a spaced parallel plane extending continuously across said wall plate and terminating near the opposite edges thereof, the width of said panel being at least twice the distance between said planes, and obliquely extending portions connecting the portions in the two planes at both sides and ends.

8. In a car wall, a metallic wall plate having marginal portions at the sides and ends in the same general plane, an embossed portion intermediate said marginal portions in a spaced parallel plane and being of a width equal to at least twice the distance between said planes, and obliquely extending portions connecting the portions in the two planes at both sides and ends.

9. A car wall comprising a metallic plate having parallel portions lying in spaced planes, a wooden strip of rectangular cross-section and of a thickness corresponding to the space between said planes, means for securing said strip to said plate in one of said planes with its opposite face lying flush with the other plane, and a wooden lining bearing against said plate in the latter plane and said strip and secured to the strip.

10. In a car wall, an extended metallic plate composed of a plurality of sections having their adjacent edge portions overlapping and rigidly secured to each other, each section comprising flat marginal portions at sides and ends, an embossed panel portion intermediate said marginal portions in a spaced parallel plane and connecting obliquely extending portions between said panel portion and marginal portion at both sides and ends, a wooden strip of rectangular cross section of a thickness corresponding to the depth of said panel portion and of no greater width, means for securing said strip to said panel portion with its opposite face lying flush with the marginal side portions, and a wooden lining formed of strips extending transversely to said panel portion lying against said wooden strips and side marginal portions of said plate and being secured to said strips.

11. In a railway car, the combination of flanged frame members, a metallic wall plate

5 having marginal portions at the sides and ends in the same general plane, and an embossed panel portion intermediate said marginal portions in a spaced parallel plane, and obliquely extending portions connecting the portions in the two planes at both sides and ends, said frame members secured to said wall plate and positioned perpendicular to the longitudinal axis of the panel 10 and said panel extending uninterruptedly between the oblique and marginal portions secured to said frame members.

12. In a railway car, the combination of flanged frame members, a plurality of wall 15 plates having marginal portions at the sides and ends in the same general plane, and an embossed panel portion intermediate said marginal portions in a spaced parallel plane, and obliquely extending portions connecting the portions in the two planes at both sides and ends, some of said wall plates secured to said frame members at two opposite edges and secured to the adjacent wall plates at the other two opposite edges and 20 said panel portion extending uninterruptedly between said frame members.

13. In a car wall, a metallic wall plate having marginal portions at the sides and ends in different planes, an embossed panel portion intermediate said marginal portions in a plane spaced from and parallel to both before-mentioned planes, and obliquely extending portions connecting the portions in the several planes at both sides and ends said panel extending uninterruptedly between the oblique and marginal portions at 30 opposite ends thereof. 35

14. In a railway car, the combination of flanged frame members, a plurality of metallic wall plates, each wall plate having an embossed panel portion and portions surrounding said embossed portion in a spaced parallel plane, and oblique portions connecting the portions in the two planes, said wall plates secured to said frame members at two opposite edges and secured to adjacent wall plates at the other two opposite edges and said panel portion extending uninterruptedly between said frame members at opposite ends thereof. 45 50

In testimony whereof I affix my signature.
FREDERICK M. WHYTE.
